UNITED STATES PATENT OFFICE

FAY H. MARTIN, OF WOONSOCKET, RHODE ISLAND, ASSIGNOR, BY MESNE ASSIGNMENTS,
TO WHITIN MACHINE WORKS, OF WHITINSVILLE, MASSACHUSETTS, A CORPOR-
ATION OF MASSACHUSETTS

CREEL

Application filed January 8, 1929. Serial No. 331,044.

The invention comprises various features applicable in the case of creels on the order of those which are employed in various manufacturing processes for supporting, in convenient relations, for the paying-out of the material wound thereon, bobbins, spools, or the like, loaded with supplies of the rovings, yarns, and the like, which are to be operated upon.

10 One portion of the invention has relation to creels of the class in which the supply-bobbins, spools, or other wound masses, are supported in place, conveniently for the delivery of their contents, upon bobbin-supporting structural elements extending longitudinally of a machine with which the creel is associated. This portion of the invention resides in a creel having the essential longitudinally-extending bobbin-supporting elements there- 15 of of shell-like curvilinear cross-section, preferably constituted by tubes. It includes, further, a creel-frame construction having the said shell-like elements provided with steps for the feet or pintles of bobbin-sup- 20 porting skewers or spindles, and with skewer- tip retainers by which the skewers or spindles and the bobbins with which they are associated are maintained in upright positions suitable for paying out from the bobbins the ma- 25 terial carried thereby.

Other portions of the invention have relation to holders for the said steps, and to skewer-tip retainers. These portions of the invention reside in step-holders and skewer- 30 tip retainers embodying the novel character- 35

istic features.

The features of the invention are illus- 40

trated by the accompanying drawing, in which,—

40 Fig. 1 shows in vertical section two rails

of a creel, and in elevation a bobbin carrying

a load of roving, and illustrates the features

of the invention.

Fig. 2 is a front elevation of a portion of

45 the length of one of the rails of Fig. 1.

Fig. 3 is a top or plan view of the said

portion.

Fig. 4 is a view in cross-section on line 4, 4,

of Fig. 2.

50 Figs. 5, 6, 7, are respectively a side eleva-

tion, a front elevation, and a top or plan view of one of the step-holders.

Figs. 8 and 9 are respectively a side ele- 55

vation and a plan view of a step.

Fig. 10 shows separately a skewer-tip re- 55

tainer like those of Figs. 1 to 4.

The features of the invention are capable of employment in creels in general. They will be described with reference, more par- 60

ticularly, to employment in a roving-bobbin

creel, such, for instance, as one for a roving- 65

frame, a spinning-mule, or a spinning-frame,

as the case may be.

Inasmuch as a creel employed in connec- 70

tion with one of the named machines is of

considerable length between one end thereof

and the other, and contains in its general

make-up constructional features that are not

involved in the invention, and inasmuch as

the invention has reference to only the lon- 75

gitudinally-extending bobbin-supporting ele-

ments of a creel, and the adjuncts by means

of which bobbin-supporting skewers are

mounted in connection with such elements,

the drawing has been restricted to short por- 80

tions of the length of two rails 1, 1, and to

the adjunctive features in connection with

such portions. This extent of illustration

will suffice for making clear the disclosure of

the features and principles, of the invention

80

which follows later herein. The said two

rails 1, 1, are supposed to be ones which are

employed at intermediate heights in a creel.

In the drawing, each of the rails 1, 1, is

equipped with a series of step-holders 2, 2,

and a series of steps 3, 3, one thereof mounted

in connection with each step-holder; and

with a series of tip-retainers 4, 4. The steps

3, 3, may be composed of any material suit-

able for the purposes involved, for instance

90 porcelain. The step-holders 2, 2, that are

shown in the drawing as holding the steps in

place in connection with the rails, and sup-

porting the steps vertically, are composed of

suitable material, usually metal. They are

95 cup-shaped, so as to enable them to contain

steps, and they are combined with the rails

1, 1, through being seated in holes in the

tops of the said rails 1, 1. The steps are seated

100 within the step-holders. The skewer-tip en-

- gaging portions of the tip-retainers 4, 4, that are carried by a rail 1 project from one side of such rail, and in such relations to the co-operating steps below them that in the case 5 of a bobbin-skewer 5 having its foot or pintle stepped in one of the said steps at the lower level and its tip, above the upper end of the bobbin 6 loaded with roving 7 that is mounted upon said bobbin-skewer, extending up 10 alongside such side of the rail in question, such tip may be encircled by one of the said tip-retainers, whereby the said bobbin-skewer and the bobbin mounted thereon are supported in upright position.
- 15 The tip-retainer 4 shown in Fig. 1 in connection with the lower rail will serve in practice to confine the tip of a bobbin-skewer that is stepped below such rail in a step carried by a still lower rail (or other support), 20 not shown; the step shown in connection with the upper rail will serve to support the foot or pintle of a bobbin-skewer that is restrained at its tip by a tip-retainer carried by a higher rail (or other support), not shown. The 25 number of rows or banks, one above another, of supply-bobbins provided for in the construction of a creel varies in practice, and accordingly the number of rails, disposed one above another, in a creel embodying the features 30 of the invention, varies in practice. Every rail of a creel except the bottom rail thereof is equipped with a tip-retainer disposed above a step located below such rail, so that such tip-retainer may encircle the tip 35 of a bobbin-carrying skewer stepped in such step, while keeping such skewer and the associated bobbin upright.
- Heretofore in general practice the longitudinally-extending bobbin-sustaining elements 40 of a roving creel have consisted of boards or of metal plates. Beams sometimes have been employed. As indicated at the outset herein, one portion of the present invention consists in a roving-creel construction 45 characterized by longitudinally-extending bobbin-sustaining shell-like elements of curvilinear cross-section. The drawing shows tubular rails 1, 1, composed of tubing having bobbin-skewer steps mounted at the upper 50 side of the shell or wall thereof, with tip-retainers applied so as to project horizontally from the vertically curved surface at one side of said shell or wall.
- The tubing is of suitable dimensions (diameter, thickness of shell or wall,) to give the 55 requisite strength, as well as to give sufficient stiffness to prevent sagging of the rails between supports under the weight of the rails themselves and the superadded weight of the 60 loads carried in practice, etc. Rails made of tubing have various advantages over boards, wooden beams, flanged and other plates, and other forms of the said longitudinally-extending bobbin-sustaining elements. They are 65 lighter than the boards or plates heretofore

employed, or than wooden beams. The amount of space occupied by them is less. In brief, I regard tubes as ideal for the bobbin-supporting rails of a creel, by reason of their possessing a maximum of rigidity and 70 strength combined with lightness. The use thereof enables the use of wood to be avoided, and provides for the production of a creel of all-metal frame-structure, if desired. The tubular rails 1, 1, will serve indefinitely without sagging. They are not liable to change of shape as in the case of metal plates, and are free from the liability to warping or checking that is experienced in the case of wood. Lint 75 or fluff and waste do not accumulate upon cylindrical rails to the same extent as upon flat topped boards, plates, and wooden beams. Cylindrical rails are very easily cleaned. Many of the advantages that are incident to the use of cylindrical tubes may be attained 80 through the employment of semi-cylindrical and the like trough-shaped rails applied with the convex sides thereof uppermost, which I regard as within the scope of my invention, in the broader phase of the latter.

The mode of application of steps in connection with rails such as have been described as embodying the first portion of the invention may vary in practice. As a second portion of the invention, I mount the steps within 85 holes in the tops of the rails in such manner that the steps shall be contained wholly, or almost so, within the enclosure of the shells or walls of the hollow rails, and by reason thereof shall be thereby enclosed and protected from dust, flyings or droppings, and from 90 blows or the like tending to injure or displace the same. The steps may be combined directly with the rails, without the intervention of step-holders, but I find it advantageous to employ these latter, to which, as another portion of the invention, I give characteristic features by means of which they are adapted for such employment. Having reference, now, to the step-holders and steps:—

The cup-shaped step-holders 2, 2, seated as aforesaid in holes in the tops of the rails 1, 1, have around their open-mouthed tops outturned flanges 21, 21, which extend outward over the margins of the said holes, and rest upon such margins as indicated in the drawing, to afford vertical support to the step-holders, and steps, and to close the said holes around the steps and step-holders. To 100 enable the flange of a step-holder to lie flatwise against the margin of a hole in a rail of curvilinear cross-section, around the entire circuit of such hole, the top of the step-holder, and the flange outstanding therefrom, are shaped to conform vertically with said margin. Thus, the said top and flange are formed with convex rises at the sides as in Figs. 4 and 5, corresponding with the convexity of the top of a rail, and with dips at 105 front and rear, as in Figs. 2 and 6, corre- 110

sponding with the depression of the said margin at front and rear. In this instance the steps and step-holders are circular in horizontal cross-section, although the cross-sectional shape may be varied if found desirable, and in order to conform to the circular shape of the step-holders the holes in the tube are circular, and consequently the flange of a step-holder is given concave dips at front and rear to correspond with the form of the hole-margin at front and rear. As an advantageous feature of construction, to facilitate insertion of a step into a step-holder, and removal therefrom, the step-holder preferably 10 tapers interiorly slightly from top to bottom, as in different views of the drawing, and the step is formed with a corresponding taper. At 22, Figs. 1 and 7, is a hole that is made through the bottom of a step-holder, to provide for the application of a suitable tool to eject a step from its seat in the step-holder. At 221 is a hole in the bottom of the tubular rail, through which such tool may be extended upward to effect such ejection after the step-holder and contained step have been fastened 20 in place in the rail. The step-holders are shown provided with tangs or tongues 23, 23, at opposite sides thereof, formed by making U-shaped incisions through the shell of a step-holder. The said tangs are permitted to remain in the plane of the metal, as in Figs. 5 and 7 and in full lines in Fig. 6, until after the step-holders have been inserted into the holes in the tubular rail, so as to facilitate 30 introduction of a step-holder into the hole in which it is to be mounted. After insertion of the step-holder, it is secured in place in a rail by turning the tongues outward, as indicated by dotted lines in Figs. 2, 3, 4, and 6, into position to engage with the inner surface 40 of the wall or shell of the rail as in Figs. 2, 3, 4, to ensure against accidental dislodgement of a step-holder, as in wiping lint from the rail, or otherwise.

45 In the drawing, the top of a step occupying a step-holder is, as is preferable in practice, almost flush with the outturned flange of the step-holder, and inasmuch as the said flange fits flatwise and snugly upon the convex upper surface of the cylindrical tubular rail to which it is applied, there exists very little in the way of projections or depressions to accumulate or detain lint and the like. In virtue of the features which have just been 50 set forth, the step-holders and steps are mainly contained within the tubular rails 1, 1, and are enclosed by the latter so as to be shielded against blows and resulting injury, and against dislodgement by blows or 60 through being acted upon in cleaning operations.

Having reference, now, to the improved tip-retaining means by which the tips or upper ends of the bobbin-carrying skewers, 65 stepped upon the skewer-steps just described,

are combined so as to keep in the desired upright positions the said skewers and the bobbins that are mounted thereon:—

It is very desirable that the operations involved in mounting a bobbin in a creel should be simple and should be capable of being performed as conveniently and as quickly as possible. It is desirable, also, that it should be possible for an attendant to mount a bobbin in a creel through the employment of one hand only. The tip-retainers 4, 4, of the invention have been designed with the object in view of serving these ends, and with the further objective of providing a type of tip-retainer adapted for convenient and secure application and attachment to tubular rails such as those shown in the drawing. The said tip-retainers 4, 4, comprise wires of U or staple-form, which are combined with the tubular rails 1, 1, of the creel with the bend 70 of the U projecting outward from the surface of the rail to which such wire is applied. The bend stands out from the said surface, and the two legs of the U are spaced widely apart, these two factors serving to provide an eye proportioned properly to contain a skewer-tip, as well as to permit sufficient play and free turning of the tip within such eye. By reason of the wide spacing of the said legs 80 apart horizontally from each other between the points where the legs of the U intersect the surface of the rail, no obstruction is presented in the case of a skewer-tip contacting with the convex surface of the lower portion 90 of the rail and pushed upward upon such 100 surface endwise into the eye. This operation admits of being performed quickly. The curved surface of the rail guides the skewer-tip into the inner portion of the eye, so that, provided the said tip has been alined with the opening of the eye, and that lateral deviation from alinement with said opening is avoided, the introduction of the tip into the 105 eye takes place readily. The operation of mounting an associated bobbin and skewer 110 in place in a creel is capable of being performed by one hand holding the associated bobbin and skewer, without the assistance of the other hand, by operations involving placing the tip against the convex surface of 115 a rail below a tip-retainer, sliding the tip upward over said surface into the opening of the tip-retainer, and dropping the foot of the skewer into the properly related step 120 provided below.

The construction of the tip-retainer may vary somewhat in practice. In the case of the illustrated tip-retainer the latter has one long leg and one short leg. The long leg extends horizontally, diametrically across the 125 tubular rail, such leg occupying holes in the shell or wall of the rail at opposite sides of the latter and being made fast in place by riveting at its extremity. The portion of such extremity which occupies the corre- 130

sponding hole in the said shell or wall is reduced in diameter to produce a shoulder 41 which, through engagement with the inner surface of such shell or wall prevents 5 displacement of the tip-retainer in one direction, while the burr on the exposed outer portion of the long leg prevents displacement in the opposite direction. The short leg occupies a hole in the shell or wall at the side 10 at which the eye is located, but in this instance extends only a short distance within the tubular rail. The engagement of the two legs of the tip-retainer within holes in the shell or wall of the tubular rail at points 15 separated from each other prevents the tip-retainer from turning so as to displace the eye.

The principles and advantages of the tip-retainer may be utilized through application 20 of the tip-retainer to creel-rails of other kinds and forms.

As a material advantage of a creel-rail that is cylindrical in cross-section, as in the case of the creel-rails that are shown in the drawing, it is to be noted that even if a skewer-tip 25 should strike against the under side of the rail in the performance of skewering, it will deflect upwardly alongside the creel-rail without being arrested as it would be if carried up against the under side of a plate, 30 rectangular beam, or other element of the like class.

What is claimed as the invention is:—

1. A creel construction characterized by 35 longitudinally-extending bobbin-sustaining elements consisting of tubular rails composed of tubing having combined therewith bobbin-skewer steps mounted in openings in the upper side of the shell or wall thereof, with 40 skewer-tip retainers projecting from the vertically-curved surface of the shell or wall.

2. In a creel, the combination comprising 45 a longitudinally-extending rail of shell-like curvilinear cross-section having step-containing holes at intervals in its upper convexity, and step-holders occupying such holes, enclosed and protected within the rail.

3. In a creel, the combination comprising 50 a longitudinally-extending rail of curvilinear cross-section having step-containing holes at intervals in its upper convexity, and step-holders occupying such holes having the tops thereof conformed closely around the respective holes to the curvilinear external contour of the rail so as to avoid lint-detaining projections and obstructions to cleaning operations.

4. In a creel, the combination comprising 60 a longitudinally-extending rail of curvilinear cross-section having step-containing circular holes at intervals in its upper convexity, and step-holders circular in cross-section occupying such holes having the tops thereof con- 65 formed closely around the respective circular

holes to the curvilinear external contour of the rail by means of lateral convex rises and front and rear dips, so as to avoid lint-detaining projections and obstructions to cleaning operations. 70

5. In a creel, the combination comprising a longitudinally-extending rail of curvilinear cross-section having step-containing circular holes at intervals in its upper convexity, and step-holders circular in cross-section occupying such holes having the tops thereof conformed closely around the respective circular holes to the curvilinear external contour of the rail by means of lateral convex rises and front and rear dips, so as to avoid lint-detaining projections and obstructions to cleaning operations, with the top of a step-holder furnished with an outturned flange overlying the margin of the hole occupied by the step-holder. 80

6. In a creel, the combination with a creel-rail, of a tip-guide constituted by a U-shaped member with the bend thereof projecting from the creel-rail and with the surface of said rail adapted to constitute a guide for deflecting a skewer-tip into the opening of the U. 85

7. In a creel, the combination with a creel-rail, of a tip-guide, constituted by a U-shaped member with the bend thereof projecting from the surface of the creel-rail, and with the legs of the U spaced apart so that the surface of the rail will guide a skewer-tip into the opening of the U when such skewer-tip is slid upward over said surface. 90

8. In a creel, the combination with a creel-rail of curvilinear cross-section, of a tip-guide, constituted by a U-shaped member with the bend thereof projecting from the vertically curved surface of the creel-rail, and with the legs of the U spaced apart so that the surface of the rail will guide a skewer-tip into the opening of the U, when the said tip is slid upward over the said vertically curved surface. 105

9. In a creel, the combination with a tubular creel-rail, of a tip-retainer comprising a wire extending diametrically across the rail, said wire of U shape with its legs occupying holes in the shell or wall of the rail, and with the bend of the U projecting from the surface of the rail. 115

10. In a creel, the combination with a tubular creel-rail, of a tip-retainer comprising a wire extending diametrically across the rail, said wire of U-shape, with its legs occupying holes in the shell or wall of the rail, and with the bend of the U projecting from the surface of the rail, with the legs of the U spaced apart horizontally at the said surface. 120

11. In a creel, the combination with a longitudinally-extending rail, of a skewer-tip retainer of U-shape, the bend of which projects from one side of the rail for the purposes of a skewer-tip-retaining eye, with one leg 130

extended through the rail and riveted to fasten the retainer in the rail, and with the other leg engaged with the rail at a distance horizontally from the first leg making the included portion of the rail-side a substantial part of the said eye.

12. In a creel, the combination comprising a longitudinally-extending bobbin-supporting rail of shell-like curvilinear cross-section having step-containing holes at intervals in its upper convexity, and steps occupying such holes, enclosed and protected within the shell.

13. A creel construction characterized by longitudinally-extending bobbin-sustaining elements consisting of tubular rails composed of tubing of curvilinear cross-section having combined therewith bobbin-skewer steps and skewer-tip-retainers.
